RIDING MOWER

Robert B. Mead, Wilmington, Ohio, assignor to Mast-Foos
Manufacturing Company, Inc., Springfield, Ohio

Filed Apr. 2, 1970, Ser. No. 22,199

Term of patent 14 years

Int. Cl. D15—03

U.S. Cl. D40—1

FIG-1

FIG-2

FIG-3

FIG-4

FIG-6

FIG-7

FIG. 1 is a side elevation view of a riding mower in accordance with my invention;

FIG. 2 is a top view of the riding mower shown in FIG. 1;

FIG. 3 is an opposite side view of my design;

FIG. 4 is a rear elevation view;

FIG. 5 is a front elevation view of my design; and

FIGS. 6 and 7 respectively show opposite perspective views illustrating a modification of my design illustrated in FIGS. 1 through 5 of the drawings.

I claim:

The ornamental design for riding mower, substantially as shown and described.
